UNITED STATES PATENT OFFICE.

JOHN C. BASH, OF BEAVER FALLS, PENNSYLVANIA.

COMBINED COAL AND GAS RANGE.

1,284,044.

Specification of Letters Patent.

Patented Nov. 5, 1918.

Application filed August 23, 1917. Serial No. 187,737.

To all whom it may concern:

Be it known that I, JOHN C. BASH, a resident of Beaver Falls, in the county of Beaver and State of Pennsylvania, have invented a new and useful Improvement in Combined Coal and Gas Ranges; and I do hereby declare the following to be a full, clear, and exact description thereof.

My invention relates to stoves and more particularly to combined coal and gas stoves or ranges, and has for one of its objects to provide a stove of this class that may be easily changed from gas to coal operation, and also one in which the gas and coal will be used as a source of heat at the same time.

A further object is to provide a novel oven construction which will operate with either coal or gas and also one which will have a new and novel ventilating means.

A still further object is to provide a novel top plate and bottom oven plate of similar construction in which the burners are formed, making a novel and integral construction.

In the drawings, I have shown a preferred form of my invention, but I wish it understood that various changes in detail and design may be made within the scope of the appended claims without departing from the spirit of my invention.

In the drawings,

Figure 1 is a front elevation of a stove constructed according to my invention, partly broken away to show the interior construction;

Fig. 2 is a top plan view of the stove burner plate;

Fig. 3 is a view thereof on the line 3—3 of Fig. 2;

Fig. 4 is a top plan view of the bottom oven burner plate;

Figs. 5 and 6 are detail views of the oven door showing my improved air inlet;

Fig. 7 is a detail view of one of the burner tops;

Fig. 8 is a detail fragmentary view showing the oven door and its relation to the oven shelf,

Fig. 9 is a plan view of the oven shelf.

Referring more particularly to the drawings, the numeral 2 designates the base of my stove which is of well known construction, on which is supported a body portion consisting of sides 3 and 4, front 5, back 6,

and top 7 having the usual openings and closures common to coal ranges.

To the one side and within the body portion is formed the oven 8 which is of novel design peculiar to my combination coal and gas stove. Formed on the sides of the oven 8 are a plurality of inwardly extending flanges or lugs 9 spaced one above the other on which is removably mounted a bottom or shelf member 10 when the oven is heated by gas, having its side portions cut away forming recesses 12 through which the heat from a suitable burner spaced below said plate is adapted to flow and be directed inwardly by the flanges or lugs 9. Shelf member 10 also has a suitable centrally arranged recess closed by a lid or cover 10' which is flush with the general plane of the member 10.

The bottom plate of my oven comprises a rectangular member 11 which is formed of cast metal, and a burner portion consisting of a conduit 13 terminating in a ring portion 14 is cast therein, the ring portion having an open top closed by removable ring plate 15 having suitable apertures 16 through which the gas may flow, and being secured to the plate as at 17 or in any other desired manner.

It will be understood that the usual flue or heat conduit extends down and under the oven and connects with the flue outlet 18 as in all well known constructions of coal stove ranges.

Within the oven 8 and secured to the top is a flue or ventilating member 19 comprising a three sided member which is adapted to allow an exit of the burnt gases, and also provide for the escape of the fumes from the cooking. The member 19 is provided with a suitable damper or valve 19'.

The oven is provided with a hinged door 20 having a surrounding flange 21 around its edge and having a ventilator or air inlet 22 in the lower portion thereof for use when gas is used. The air inlet 22 comprises an aperture having inwardly extending side flanges 23 which are formed on the door 20 and are of equal depth with the flange 21 on said door and such flanges 23 abut the shelf 10 of the oven, while a hinged closure 24 for said aperture is connected to the flanges 23 so as to open inwardly under the shelf 10 to form a top portion, and is held in such position by any desired means such as by friction between the parts. It will be read-

ily seen that with such a construction, the inflowing air will pass directly to the burner or point of combustion and will not enter the baking chamber.

5 Located to the one side and extending partially over the oven portion 8 is a gas heated portion comprising a burner plate 25 similar in construction with the bottom oven plate 11 with the exception that it has a plurality of burners cast therein all similar to the burner 13, 14, 15 in the plate 11, and similarly numbered. Extending around the plate 25 is a rim or frame 26 adapted to support a suitable cover plate 27 having apertures therein on a line with the burners in the plate 25 closed by covers or lids 28.

10 While I have shown my improvements as being applied to a combined coal and gas stove or range, it will be apparent that the same improvements may be applied to stoves or ranges adapted to use gas alone as a fuel.

15 Having thus described my invention, what I claim is:—

1. In a stove having an oven portion, a hinged door for said oven, said door having an aperture in its bottom edge, a removable shelf in said oven, a burner under said shelf, a hinged closure member adapted to close said aperture, said closure being adapted to be opened inwardly and abut said shelf thereby forming an air passage to said burner, and means for holding said last named closure in its open position.

2. In a stove, an oven portion, said oven

portion having a removable shelf member, 35 a burner below said member, a flue member arranged at the top of said oven portion to carry the gases from said burner, a damper arranged at the forward end of said flue member, a hinged door for said oven, 40 said door having an aperture in its bottom edge, a hinged closure member adapted to close said aperture and adapted to be opened inwardly and abut the under side of said shelf member thereby forming an air passage to said burner, and means for holding said last named closure in its open position.

3. In a stove, an oven portion, said oven portion having a removable shelf member, a burner below said member, a flue member 50 arranged at the top of said oven portion to carry off the gases from said burner, a hinged door for said oven, said door having an aperture at the bottom edge, means for opening and closing said aperture, and means on the inner face of said door adapted to abut said shelf member to form a passage for air entering through said aperture when opened directly to the burner and prevent said air from passing upwardly to 60 the oven above said shelf member.

In testimony whereof, I the said JOHN C. BASH, have hereunto set my hand.

JOHN C. BASH.
